INKING FOUNTAIN

Filed May 31, 1929

UNITED STATES PATENT OFFICE

HARRY W. CLARK, OF WYANDOTTE COUNTY, KANSAS

INKING FOUNTAIN

Application filed May 31, 1929. Serial No. 367,339.

This invention relates to inking fountains and particularly to that type having an ink receptacle from which the ink is fed by means of a roll. This type of inking fountain which is generally used on printing presses is difficult to operate so that a constant even flow of ink will be fed to the ductor roll. This difficulty is caused by the collection of foreign material in the receptacle adjacent the point of tangency of the ink control blade with the roll. The space in the receptacle in which this foreign material collects may vary slightly as the control blade is adjusted to and from the roll to feed different quantities of ink, but is very narrow so that it is impossible to remove said foreign substances or properly mix them with the body of the ink by means of any moving member within the fountain. This difficulty is overcome in the present invention in which the fountain roll which is intermittently driven away from the control blade to feed the ink from the fountain is intermittently rotated in the opposite direction a sufficient distance to carry the accumulation of foreign substance backwardly and upwardly into the body of the ink, thus permitting a fresh supply of ink to be fed to the delivery aperture. The foreign material thus carried back into the body of the ink will mix therewith and eventually be fed from the fountain in small quantities without interfering with the free and even flow of the ink.

The principal object of this invention is the provision of an ink fountain having an ink receptacle, and ink roll for feeding ink from said receptacle, means for intermittently rotating the roll in one direction and means for intermittently reversing the direction of rotation of said roll.

With these general objects in view as well as minor objects which will appear in the course of the detailed specification, the invention will now be described with reference to the accompanying drawings illustrating a construction embodying the improvements and particularly designed for use on a printing press.

In the drawings:

Figure 1 is a plan view with parts broken

away, of an inking fountain embodying this invention;

Fig. 2 is an enlarged fragmentary end elevation of the fountain showing the roll driving mechanism;

Fig. 3 is a side elevation of the parts shown in Fig. 2;

Fig. 4 is a view similar to Fig. 2, with parts broken away and with the driving mechanism shown in solid lines, in position to reverse the direction of the roll and in dotted lines the parts are shown in position to drive the roll in the direction to feed the ink from the fountain;

Fig. 5 is an enlarged fragmentary cross section taken on line V—V of Fig. 1.

Similar reference characters designate like parts throughout the several views and the numeral 10 designates an inking fountain frame of any suitable type in which is rotatably mounted fountain feed roll 11 by means of an axle or shaft 12 passing through bearing members 13 and 14. An ink control blade 15 is mounted in frame 10 with its lower edge substantially tangent with the periphery of roll 11 and adjustable thereto and therefrom by means of blade adjusting screws 16 which are threaded into frame 10 at 17. The frame 10, roll 11, and blade 15 form an ink receptacle 18 in which ink K is placed.

The amount of ink that is fed from fountain is determined by the space between blade 15 and roller 11. This space is necessarily slight and as small foreign particles such as lint, scum, dried varnish, etc., are fed to the exit there is a tendency for them to gradually accumulate if the roll is continuously turned in the same direction, thus interfering with the proper feeding of the fountain. This is especially true where only a thin layer of ink is being fed. Furthermore, this collection of foreign material serves as a strainer that collects the pigment and permits the thin varnish to pass through without sufficient color therein.

The general construction of inking fountain just described with means for intermittently rotating the roll in only one direction is well known in the art and the new and

novel features of this invention reside especially in the novel mechanism which will now be described. Roller shaft 12 extends through bearing 14 which has an elongated hub 19 to which is rigidly attached a cam 20 by any suitable means such as screw 21. Rigidly mounted by means of pin 23 on shaft 12 adjacent cam 20 is a ratchet wheel 22 which, when rotated, rotates said shaft and the roll 11. Mounted for oscillation on shaft 12 is a bell-crank lever 24 having arms 25 and 26. Mounted on arm 25 in axial alinement with shaft 12 is a bolt 27 on which is mounted a pawl 28 positioned in operative relation with ratchet 22. Pawl 28 is provided at its outer portion with a pin 29 which normally rides on the outer periphery of cam 20 and holds said pawl out of engagement with ratchet teeth on ratchet 22. Pawl 28 is also provided with a pin 30 to which is attached one end of a tension spring 31 while the other end of said spring is attached to pin 50 carried by lever 24, thereby exerting an inward pull on said pawl. When the pin 29 is moved to the lower portion of the cam 20 as shown by dotted lines in Fig. 4, pawl 28 will move inwardly and engage the teeth of ratchet 22, thus driving the roll 11 forward and feeding the ink from the fountain.

Shaft 12 is provided at its outer extremity with the ratchet wheel 32 having one or more teeth 33 formed therein, and being rigidly attached to shaft 12 by means of set screw 34. Positioned intermediate ratchet 32 and lever 24 and encompassing shaft 12 is a stationary cam 35 which is shown attached to frame 10 by means of screws 36. Pivotaly mounted on bolt 27 is a pawl 37 which is normally held out of engagement with teeth 33 by a pin 38 carried thereby and which is adapted to rest on the outer periphery of cam 35. At each oscillation of the lever 24 the pin rides off and on the raised portion 35' of cam 35. The forward movement of the ratchet wheel 22 is intermittent and through a short arc equal to about one or two of the ratchet teeth so that pawl 37 will not engage one of the teeth 33 at each forward movement of the inking roll, but during a part of the oscillations will ride on the smooth periphery of ratchet 32 and will only engage teeth 33 when they are in the line of travel of said pawl. To maintain pawl 37 under tension against the cam, a tension spring 40 is mounted at its opposite ends on pins 30 and 38 respectively.

An operating rod 42 is pivotally mounted at one end to arm 26 by means of member 41 and at its other end to a wrist pin 43 which in turn is mounted on an eccentric wheel 44 rigidly mounted on any suitable power shaft 45. To vary the relative positions of the cams and pawls in order to vary the forward and rearward movement of the roll 11 an adjust-

ing threaded section 46 is provided in operating rod 42.

Briefly, the operation of this device is as follows: Shaft 45 is rotated constantly in one direction by any suitable power, thereby rotating wheel 44 and the wrist pin 43 to which the operating rod 42 is attached. Through the movement of operating rod 42 an oscillation of lever 24 is obtained. Referring to Figs. 2 and 4, when the lever is moved clockwise and pin 29 drops into the recess in cam 20, pawl 28 will engage ratchet teeth in 22 and move said ratchet and the attached members forwardly, thereby feeding ink from the fountain. During this movement the pawl 37 will be moving in the inoperative direction, but when the direction of the lever 24 is anticlockwise and the pin 38 rides off from the raised portion 35' of cam 35 and the tooth 33 is in the position as shown in Fig. 2, said pawl will engage tooth 33 and drive ratchet 32, shaft 12, and roll 11, in a backward direction a sufficient distance to carry any accumulation of foreign material away from the ink exit. It is apparent that with only two ratchet teeth 33 as shown, that there will not be a backward movement of the roll at each forward movement. This, however, may be varied to any desired relative movements even to the extent of moving the roll backward at each forward movement, but through a smaller arc.

While I have illustrated and described what is now deemed to constitute the preferred form of embodiment of the invention, I desire to reserve the right to make all such formal changes or modifications as may fairly fall within the scope of the appended claims.

Having described the invention, what I claim is:

1. An inking fountain comprising an ink receptacle, an ink feed roll, and means for intermittently rotating said roll through arcs of different degrees in opposite directions.

2. An inking fountain comprising an ink receptacle, an ink feed roll, means for intermittently rotating said roll in one direction through a given number of degrees, and means for intermittently reversing the direction of rotation of said roll and moving the same through a less number of degrees than the first named number of degrees.

3. An inking fountain comprising an ink receptacle, an ink feed roll, means for intermittently rotating said roll in opposite directions, and means for adjusting said first named means whereby the relative degree of rotation in opposite directions may be varied.

4. An inking fountain comprising an ink receptacle, an ink feed roll, means for intermittently rotating said roll forwardly and backwardly, said means being adapted to

rotate said roll forwardly a plurality of times to each backward rotation thereof.

5. An inking fountain comprising an ink receptacle, an ink feed roll, means for intermittently rotating said roll forwardly and backwardly, said means being adapted to move the roll farther forward than backward.

10 6. An inking fountain comprising an ink receptacle, an ink feed roll, means for intermittently rotating said roll outwardly to feed ink from said fountain, and means for intermittently rotating the roll inwardly through a smaller arc than it is rotated forwardly.

15 7. An inking fountain comprising an ink receptacle, an ink feed roll having an axle, a ratchet wheel secured to said axle, a pawl adapted to be oscillated to intermittently rotate said ratchet wheel, a second ratchet wheel secured to said axle, and a pawl 20 adapted to be oscillated to rotate said second ratchet wheel in the opposite direction.

25 8. An inking fountain comprising an ink receptacle, an ink feed roll, means for intermittently rotating feed roll in one direction to feed ink from said receptacle, means for intermittently rotating feed roll in the opposite direction, a cam, and adjustable means to vary the relative position of the cam and said first named means to vary the degree of rotation of said feed roll.

In testimony whereof, I hereunto affix my signature.

HARRY W. CLARK.
